AIR CONDITIONING APPARATUS

Henry S. Woodruff, Larchmont, N. Y., assignor
to Heating Ventilating & Air Conditioning Co.
Inc., New York, N. Y., a corporation of New
York

Application February 9, 1937, Serial No. 124,816

4 Claims. (Cl. 62—115)

This invention is directed to an improvement in air conditioning equipment, and has for one of its objects the provision of a simple, compact, relatively inexpensive and very efficient unit.

5 My improved equipment, in general, comprises an enclosing cabinet within which I provide a compressor, a motor for driving the same, a condenser, a fan for air cooling the compressor, motor and condenser, conditioning or evaporating 10 coils being provided in the upper part of the enclosing cabinet together with an air circulating fan by which air to be conditioned is drawn into the cabinet and then discharged therefrom. The compressor, motor and fans are vertically disposed 15 and in vertical alignment and the condenser is of the coil type and surrounds the motor; this construction, as will be appreciated, conserving floor space.

The air conditioning equipment illustrated in 20 the accompanying drawings also includes new and novel means for re-evaporating and disposing of moisture condensing on the cooling or conditioning coils. This feature is claimed in my copending application Serial No. 106,547, filed 25 October 20, 1936, of which the present application is a division, and this structure, therefore, will not be described in great detail herein.

In the drawings:

Fig. 1 is a sectional elevational view of an embodiment of my invention;

Fig. 2 is a section on the line 2—2 of Fig. 1; and

Fig. 3 is a section on the line 3—3 of Fig. 1.

Referring to the drawings in detail: 2 designates an enclosing cabinet which may be of wood or metal and is felt lined for sound-deadening or sound-absorbing purposes, as shown at 3.

At the upper part of the cabinet is an air conditioning chamber 4 which will be referred to 40 more in detail hereinafter. The cabinet 2 is provided in its side walls with air intake grilles 5 and in its roof with air discharge grilles 6. The grilles 5 are equipped with filters 7 which are removable for cleaning or for replacement for filtering the 45 air passing into the chamber 4 through the grilles 5.

8 designates the base of my improved equipment, this base supporting the cabinet 2 which is 50 removably mounted thereon.

55 Within the lower part of the cabinet 2, that is to say, below the conditioning chamber 4 is a compressor 9 driven by an electric motor 10, the motor being disposed vertically and in vertical alignment with the compressor.

As will be seen from the drawings, the arma-

ture shaft 11 of the motor is extended vertically above the motor and carries a centrifugal fan 12. This fan is positioned below a partition 13 which extends transversely of the cabinet and which constitutes the floor or lower wall of the conditioning chamber 4, and the armature shaft 11 extends through this floor 13 and carries at its upper end an air circulating fan 14 which is located within the conditioning chamber 4, this fan being provided for the purpose of drawing air 10 through the grilles 5 into the chamber 4 and discharging the air out of the chamber to the surrounding atmosphere through discharge grilles 6.

Surrounding the motor 10 are banks of condenser coils 15.

The partition 13 constituting the floor of the conditioning chamber 4, the centrifugal fan 12, the housing 16 for this fan, compressor 9, driving motor 10 and the condenser coils 15 are all mounted within a cylindrical shell 17 covered with 20 acoustic felt 18 and mounted within the cabinet 2 and extending vertically thereof. The shell 17 is supported on the base 8.

Secured to the inside of the shell 17 are mounting brackets 19 carrying the motor 10 and compressor 9, the attachment of the motor to these brackets being through a resilient connection 20. The brackets are somewhat flexible in the direction of rotation of the motor 10 to reduce to some extent the transmission of torsional stresses to 30 the shell 17. The condenser coils 15, which as above mentioned are also within the shell 17, are suspended from the the upper set of mounting brackets 19 by hangers 21.

The shell 17 is disposed eccentrically to the cabinet and is open at its lower end which provides an air intake passageway 22 from the exterior of the cabinet 2 down along the inside of the cabinet between it and the shell 17, the air passing beneath the lower end of the shell and then upwardly within the shell, finally to pass out of the cabinet through conduit 23. The air is drawn into the cabinet and discharged therefrom by the centrifugal fan 12, as will be understood, 45 and in its passage through the shell 17 air cools the compressor 9, motor 10 and condenser 15.

The air conditioning chamber 4 is provided with evaporating coils 24 mounted in hangers 25 the upper ends of which are attached to the ori- 50 fice 26 for the circulating fan 14. The lower ends of these hangers 25 are secured to the floor 13 of the conditioning chamber. It will be seen from an inspection of the drawings that the evaporating coils 24 surround the fan 14 so that all air 55

drawn into the conditioning chamber by the fan is caused to pass over these coils.

The refrigerant compressed by the compressor 9 passes by way of tubing 27 to the intake end of coils 28 which lie directly beneath and in good thermal contact with the underside of the floor or bottom 29 of the housing 16 for the fan 12.

The discharge end of the tubing 28 is connected by pipe or tubing 30 to the upper header 10 31 of the condenser coils 15 so that the refrigerant passes from the tubing 28 through the condenser coils 15 and into the liquid receiver 32. The gas passing through the tubing 30 is at the hottest part of its cycle and the tubing being in 15 thermal contact with the fan housing 16, heat is absorbed from the gas passing through this tubing, thus very materially reducing the work required of the condenser 15.

The liquid refrigerant is forced out of this receiver by the compressor 9 through tubing 33 20 which extends vertically of the cabinet along the interior of the shell 17 to the conditioning chamber 4 and expansion valve 34, the refrigerant expanding in the expansion or evaporating coils 25 24 and returning to the intake side of the compressor by way of pipe 35.

In assembling the entire internal components of my apparatus as a unit are placed upon the base 8 and secured in place after which the 30 cabinet 2 is placed in position on the base 8, or if the yielding support for the unit is at the top of the apparatus the cabinet 2 is first placed over this unitary structure after which spring connections 36 are made.

35 What I claim is:—

1. Air conditioning apparatus comprising in combination a compressor, a motor for driving the same, a cooperating condenser, an enclosing cabinet, a shell within said cabinet within 40 which the compressor, motor and condenser are mounted, said shell being open ended and spaced from the wall of the cabinet to provide for the

passage of air between the shell and cabinet, and a fan adjacent the top of the shell for drawing air through said passage and up through the shell about said motor, compressor and condenser and discharging the air to the exterior of the 5 cabinet.

2. Air conditioning apparatus comprising in combination a compressor, a motor for driving the same, a cooperating condenser, an enclosing cabinet, a yieldingly mounted shell within said 10 cabinet within which the compressor, motor and condenser are mounted, said shell being open ended and spaced from the wall of the cabinet to provide for the passage of air between the shell and cabinet, and a fan adjacent the top 15 of the shell for drawing air through said passage and up through the shell about said motor, compressor and condenser and discharging the air to the exterior of the cabinet.

3. Air conditioning apparatus comprising in 20 combination a motor, a compressor driven thereby, a condenser, an enclosing cabinet, a shell within the cabinet spaced from the cabinet walls to provide for the passage of air between the shell and cabinet, said motor, compressor and 25 condenser being yieldingly mounted within said shell, a fan housing adjacent the top of said shell, and a centrifugal fan in said housing for drawing air into the cabinet, along the space between the cabinet and shell and from thence 30 about the motor, compressor and condenser, into said housing from which it is discharged to the exterior of the cabinet.

4. Air conditioning apparatus comprising in combination, a compressor, a motor for driving 35 the same, a fan for air cooling the motor and compressor, a housing for said fan, and gas conducting means in thermal contact with said fan housing and in communication with the discharge side of said compressor. 40
